UNITED STATES PATENT OFFICE.

JOHN E. GREENAWALT, OF NEW YORK, N. Y.

SINTERING APPARATUS.

Application filed March 21, 1923. Serial No. 626,668.

To all whom it may concern:

Be it known that I, JOHN E. GREENAWALT, a citizen of the United States, residing at New York, in the county of New York and State of New York, have invented certain new and useful Improvements in Sintering Apparatus, of which the following is a specification.

My invention has relation to improvements in sintering apparatus and is directed to the method of and apparatus for igniting the charge of material to be treated. Heretofore I have used an igniting hood wherein there are a plurality of burners from which the fuel is projected under pressure in the form of a circular sheet to simultaneously ignite the surface of the charge. Examples of this method of igniting the charge may be found in my United States Patent No. 1,084,939, and my copending application Serial No. 626,669 filed March 21, 1923. However, this method, although satisfactory, involves the supplying of the fuel to the burners under considerable pressure (about forty pounds) and also requires a specially constructed burner, such as in the patent and application aforesaid.

The method of ignition about to be described in the present application requires no special burner and may be carried out with gaseous fuel at a low pressure. The gas supplied by commercial companies (at a pressure of approximately one pound) may be used with good results. Therefore, one of the objects of the present invention is to provide a method of and apparatus for igniting material to be sintered with commercial gas as a fuel, or some other suitable fluent fuel at a low pressure, since powdered coal would suffice; a further object is to obtain satisfactory igniting with a simple burner such as a perforated pipe; a still further object is to accomplish simultaneous ignition over a large surface by projecting a plurality of small jets of flame against said surface. Further and other advantages will be better apparent from a detailed description of the invention in connection with the accompanying drawings, in which—

Figure 1 is a top plan of my improved ignition apparatus with parts of the hood roof omitted; Fig. 2 is a side elevation of the apparatus with part in section; Fig. 3 is a transverse section through the apparatus on the line 3—3 of Fig. 2; Fig. 4 is a top plan of the burner with part of the fuel pipe

broken away; Fig. 5 is an enlarged cross-sectional detail through the burner on the line 5—5 of Fig. 3; Fig. 6 is an enlarged cross-sectional detail through the burner on the line 6—6 of Fig. 3; Fig. 7 is an enlarged cross-sectional detail through the burner on the line 7—7 of Fig. 3; Fig. 8 is a side elevation of about one-half of a modified form of apparatus wherein a fuel and air premixing device is used.

Referring to the drawings, and for the present to Figures 1 to 7 inclusive, H represents the igniting hood of the apparatus adapted to be placed over a sintering pan P containing a charge of material m to be treated, said pan having communication with an exhauster (not shown) connected to openings A in each end of the pan, as is well understood in the art. Said hood H comprises a supporting frame 1, a plurality of cross-roof frame members 2 resting on and secured to said frame 1, and a plurality of burners 3, each of which is supported by adjacent roof frame members 2, 2 which are spaced to receive the burners. The supporting frame 1 carries a sealing frame 4 which forms the subject-matter of my copending application Serial No. 626,667 filed March 21, 1923, and will not here be described further.

There are two burners 3, 3 supported between every two adjacent roof members 2, 2, said burners constituting a part of the hood H and extending from each side of the pan to the middle (Fig. 3). Supported in said burners on saddles 5 are fuel pipes 6, each of which is connected by a branch 7 to a manifold 8, the latter being adapted to be connected to a fuel supply main (not shown) by a swing pipe 9 connected to the manifold by the stuffing boxes 10, 10. The manifold 8 is supported through a standard 11 and block 12 by channels 13, 13, said channels being supported by brackets 14, 14 formed on the sides of frame 1. The entire apparatus is supported by wheels 15 mounted on axles 16 journaled in bearings 17 on the frame 1.

The fuel pipes 6 are each provided with a series of outlet openings o for the fuel, said openings extending along the entire length of the pipes alternately on one side and then the other thereof. The burners 3 are U-shaped in cross-section and are provided with flanges 18, 18 along their upper edges which rest upon ledges 19, 19 formed on the lower edges of adjacent roof members 2. Each burner

- 3 has a pair of lugs 20, 20 formed on its upper edges and adjacent each end thereof, said lugs projecting inwardly and serving as an abutment for blocks 21, 21 which, together with set screws 22, of which one is screwed through each block and against the pipe 6 within the burner, maintain the pipe 6 in place on the saddles 5. The burners 3 are each provided with a series of bosses 23 formed on the inside thereof alternately from side to side along the entire length of the burner, and traversing the bosses are openings o' registering with pipe openings o to form the outlet for the fuel. It will be observed that there is a slight space s between the pipe 6 and inner face of bosses 23, the object of which is to permit atmospheric air to come down into the burner (which is open at the top) and mix with the fuel as it comes from the opening o , the mixed fuel and air discharging into the hood chamber C through openings o' . The jet of gas issuing from each opening o acts as an injector in drawing air through opening o' with it. At the middle of burner 3 where pipe sections 6, 6 are connected to branch 7 by the T' the boss 23' must needs be thinner than bosses 23 in order to maintain the space s' between the burner and said boss. The spaces s , s' are quite narrow so that the gas issuing from openings o will not escape through the spaces into the atmosphere, but will pass as jets through openings o' into the chamber C. It will be observed that all of the openings o' are inclined downwardly toward the surface of the charge m in the sintering pan P, so that the jets of flame issuing from the burners will be projected downwardly against the charge. Since the jets are projected diagonally against the charge they have sufficient length to enlarge and spread out, each jet thus furnishing a larger flame to be drawn downwardly than if they were projected perpendicularly against the charge. Then too, the downward draft through the charge will be effective on the entire length of the flame jet. By virtue of the above disposition of the jets their cumulative effect, when acted upon by the draft, is to simultaneously ignite the entire surface of the charge.
- After the hood H has been positioned over the pan P and the sealing frame 4 lowered to shut off cross-currents from the charge, the swing pipe 9 is connected to the gas supply main (in any suitable manner) thus providing the burners with gas. As the jets of gas issue from the openings o they will induce air to flow downwardly through spaces s , s' forming a combustible fuel mixture which issues from openings o' . The draft is then caused to move downwardly through the charge by the exhauster (not shown) and the fuel jets ignited. The downward

draft will augment the air flow through the openings o so that there will be a plentiful supply of oxygen to support the combustion of the fuel. The flame jets will be projected some distance from the burners and will (of course) spread out as they leave the burner, thus covering the entire surface of the charge with flame which is drawn downwardly against the charge by the draft. The entire surface of the charge is thus simultaneously and thoroughly ignited in a few moments.

While in the present case a hood is provided to form an igniting chamber C, this hood (as such) may be dispensed with, leaving open the entire space above the charge except for the burners. The reason that hood is not needed in the present method of igniting the charge is because the flame jets from the large number of burner openings are projected against the entire surface of the charge instead of filling the igniting chamber with flame as is the case in my patent aforesaid.

Referring to Fig. 8, I show an igniting apparatus of which the manifold 30 for supplying the branches 31, which lead to the burner pipes, with fuel, is connected at 32 with a gas and air mixing device well known in the art (a Maxon premix being preferred) for premixing the fuel with air before it enters the burners. The gas enters the premixer through a pipe 33, and the air entering through intake openings 34, the two being thoroughly mixed within the housing 35 from which the mixture is discharged into manifold 30. In all other respects this igniting apparatus is similar to that of the main form previously described.

Having described my invention, I claim:

1. The method of igniting a charge of material to be sintered which consists in projecting a plurality of flame jets diagonally toward the charge and simultaneously therewith subjecting the charge to the action of an exhauster whereby the flame from the jets will be drawn against the surface of said charge.

2. The method of igniting a charge of material to be sintered, which consists in projecting a plurality of flame jets diagonally toward the charge from a sufficient distance to permit said jets to spread into each other, and simultaneously therewith subjecting the charge to the action of an exhauster.

3. In an igniting apparatus for material to be treated, a burner and a fuel pipe therein, said burner and fuel pipe having registering outlet openings, the openings in the burner being diagonally inclined toward the surface of the charge.

4. In an igniting apparatus for material to be sintered, a burner and a fuel pipe therein, said burner and fuel pipe each hav-

ing a plurality of outlet openings in registering relation and extending along their length on both sides, the openings in the burner being diagonally inclined toward the surface of the charge.

5. An igniting device for material to be treated comprising a frame and a plurality of burner members mounted on said frame, said members being elongated and substantially **U**-shaped in cross-section, a fuel pipe disposed within the burner member along its longitudinal axis, means for supplying fuel to said pipe, said member and pipe having registering outlet openings, and means for securing the pipe in spaced relation with the burner.

10. An igniting device for material to be treated comprising a hood, said hood embodying a plurality of burner members and

20 roof members, said burner members having fuel pipes therein, the burner members and fuel pipes having registering outlet openings, and means for permitting the passage of atmospheric air through the burner member to the burner outlet.

25 7. An igniting device for material to be treated comprising a hood, said hood being composed of a frame and a plurality of roof members supported thereby, some of said roof members constituting burners, the burners having fuel pipes therein and spaced therefrom, and the burners and pipes having registering outlet openings for the fuel mixture.

30 In testimony whereof I hereunto affix my signature:

JOHN E. GREENAWALT.
